No Drawing. Application October 6, 1933, Serial No. 692,432. In Great Britain October 19, 1932

2 Claims.

(Cl. 28-1)

This invention relates to processes for effecting a reduction in the lustre of cellulose ester and ether materials.

In U. S. Patent No. 1,554,801 is described the delustring of fibres, threads, fabrics or the like made of or containing cellulose acetate or other esters of cellulose, by the action of hot or boiling water or steam or solutions of certain substances. This method of reducing the lustre of cellulose ester and ether materials, and in particular textile materials made of or containing filaments of acetone-soluble cellulose acetate, has been employed on a very extensive scale. The

15 reduction in lustre has generally been effected by subjecting the materials to the action of an aqueous soap solution at temperatures approaching the boiling point. Usually, it is necessary, in order to obtain the desired degree of deluster, to carry out the treatment with the soap solution for a considerable time, for example from 16 1/2-4 hours or even more, the time depending for example upon the character of the fabric or other material under treatment and the temperature.

25 We have found that certain compounds of relatively high boiling point or low volatility are of great value as accelerators of the delustering action of hot aqueous media (that is, hot aqueous liquids or moist steam) on cellulose ester and ether materials. We have found, for example, that amides of organic acids, especially amides of carboxylic acids or aromatic sulphonnic acids, are capable of increasing to a marked degree the rate of delustering of cellulose ester and ether materials in hot aqueous liquids. Alternatively, they may be utilized to effect the desired degree of delustering at a lower temperature than is otherwise possible, or again for a given rate of delustering to enable the operation to be per-

40 formed at a lower temperature. For example, by dispersing or dissolving acetanilide or para-toluene sulphonamide in an aqueous soap solution, the delustering action of the latter may be increased to a marked degree. Other bodies of 45 relatively high boiling point having a plasticizing action on cellulose esters or ethers, we have found, may similarly be employed to accelerate the delustering action of hot aqueous liquids.

50 Preferably these compounds are such as have boiling points above 200° C. e. g. above 250° C. As examples of compounds or classes of compounds which may be utilized for accelerating or increasing the delustring action of hot aqueous liquids or moist steam in accordance with the

present invention mention may be made of the following:—

Carboxylic amides containing more than 6 carbon atoms, e. g. more than 8 carbon atoms, for example (a) acetylated or other acidylated aromatic amines, e. g. acetanilide or (b) amides or substituted amides such as aryl-, aralkyl-, alkyl- or oxyalkyl-amides of aromatic or hydroaromatic acids or aliphatic acids containing more than 6 carbon atoms, particularly fatty acids containing more than 10 carbon atoms, e. g. benzamide, phthalimide, benzanilide, diacetyl-p-phenylenediamine diacetyl benzidine, oleic amide or stearic amide.

Amides of sulphonic acids, for example amides or substituted amides (such as alkyl-, oxyalkyl-, aralkyl- or aryl-amides) of benzene, toluene, xylene or naphthalene sulphonic acids, e. g. p-toluene sulphonamide or its N-methyl or N-ethyl derivatives, xylene mono-methyl-sulphonamide or mixtures thereof, and di-p-toluene-sulphobenzidine. 15 20

Camphors, menthols, terpineols and other hydro-aromatic hydroxy, ketonic or other compounds of relatively high boiling point. 25

Esters, for example (a) esters of phthalic acid, benzoic acid, naphthénic acids or other aromatic or hydro-aromatic mono- or poly-carboxylic acids with phenols, aliphatic alcohols, or aromatic alcohols, e. g. benzylbenzoate, dimethyl phthalate, or diethyl phthalate or dibutyl phthalate; (b) esters of aliphatic acids especially esters containing 6 or more carbon atoms, e. g. methyl, ethyl or butyl oleate or stearate or diethyl- or dibutyl tartrate or other esters of hydroxy aliphatic acids; (c) esters of phosphoric acid, e. g. triphenyl or tricresyl phosphate or other aromatic esters; (d) esters of hydroxy acids, e. g. diethyl or dibutyl tartrate.

Ethers, e. g. dibenzyl ether.	40
Ketones, for example aromatic ketones, e. g.	

The delustering accelerators may be utilized in various ways for increasing the rate of delustering. Thus they may be dispersed or, where 45 sufficiently soluble, dissolved in the hot water or other hot aqueous liquid used and the material steeped therein until the desired degree of delustering has been attained.

The dispersion of the delustring accelerator in 50 the hot aqueous bath may be effected in any desired manner, for example by means of soap, Turkey red oil or other dispersing agent, for example any of the dispersing agents described in U. S. Patents Nos. 1,618,413, 1,618,414, 1,694,413, 55

1,690,481, 1,803,008, 1,840,572, 1,716,721, 1,928,647 and 1,959,352. It has moreover been found that the dispersion of water-insoluble accelerators may with very great advantage be assisted by the presence of solvents therefor, for example hydrocarbons, e. g. xylene or a halogen hydrocarbon, in the manner described in connection with the dispersion of dyestuffs in U. S. Patents Nos. 1,690,481 and 1,803,008.

10 Other methods of producing dispersions of the compounds used to assist delustring may however be employed, for example mechanical methods. Thus the compounds may be mechanically dispersed in water in the presence of the protective colloid, for example waste sulphite cellulose liquor, with or without a solvent for the compound, e. g. benzene, xylene or other hydrocarbon.

15 The concentration of the delustring accelerator in the delustring bath may vary within wide limits and excellent results have been obtained by utilizing it in the proportion of about 5-20 grams, e. g. 10 grams per litre of the delustring bath. The temperature of the treatment may likewise be varied within considerable limits. For example, it may be 85° C. to 95° C. or 100° C. and, in order to reduce the time of treatment as much as possible, temperatures approaching the boiling point as nearly as practicable should be employed. The accelerator may be utilized either to reduce the time of delustring at a given temperature or to enable delustring to be effected in a given time at a lower temperature than would otherwise be possible.

20 35 Another and very important method of utilizing the accelerators is that described broadly in British Patent No. 409,276, namely first to treat the materials with the compound in question and thereafter to subject them to the action of a hot aqueous bath which may or may not contain further quantities of the delustring accelerator. Thus, excellent results may be obtained by impregnating the material, for example by padding, with a relatively concentrated dispersion of the accelerator and thereafter passing the material through hot or boiling water. Under these conditions it has been found possible to effect the delustring operation by a passage of a few seconds only through a bath at or near the boiling point.

40 45 50 The dispersions of the delustring accelerators may be prepared in the same way as those intended for use in the bath treatment process referred to above. As indicated previously, the concentration may in this case be relatively high and very good results have been obtained by the use of a dispersion containing per 1000 parts 40-100 parts of delustring accelerator, e. g. 50 parts, an equal quantity of solvent, e. g. xylene and 600 parts of 50% Turkey red oil.

55 60 65 70 Preferably as explained in British Patent No. 409,276, these concentrated dispersions of the delustring accelerators are applied to the materials at relatively high temperature and the materials are batched prior to delustring. The delustring of the impregnated materials may then be very simply effected by passing them through a bath of water maintained as near the boiling point as possible. Very good results may be obtained when a bath of plain water is employed, though if desired it may contain any desired additions, for example soaps and/or a further quantity of delustring accelerator.

75 The invention is not restricted to accelerating the delustring action of hot aqueous liquids. In

a similar manner the delustring action of moist steam may be facilitated. Thus, the cellulose acetate or other cellulose ester or ether material impregnated with the delustring accelerator may be passed through a suitable apparatus in which it is subjected to the action of moist steam. The incorporation of the delustring accelerator may be effected in a manner similar to that described for the preparation of materials to be delusted by passage through or treatment with a bath of hot water or other hot aqueous liquids.

80 85 90 95 100 The hereinbefore-mentioned compounds may also be utilized as delustring accelerators in the production of pattern effects upon cellulose ester or ether materials. Thus, they may be applied locally to the materials in any desired pattern and the materials thereafter subjected to the action of hot water or moist steam, in the manner described broadly in U. S. Patent No. 1,826,608. In this manner valuable delusted effects upon a lustrous ground may be obtained.

105 110 115 120 125 An important application of the present invention is in connection with the removal of glaze marks from cellulose acetate fabrics. It has been found for example that by subjecting a material bearing glaze marks (e. g. marks produced by improper ironing) to the action of an aqueous solution of p-toluene sulphonamide of 3-10 grams e. g. 4 grams per litre strength at about 80-85° C. the glaze marks may be removed without substantial delustring of the material taking place. It appears that preferential delustring of the glazed portions is effected. We have further found that other delustring accelerators may be similarly employed. For such glaze removal the conditions of concentration of agent, temperature and duration of treatment should be such as do not lead to any substantial delustring of the unglazed portions of the material.

EXAMPLE 2

To remove "glaze marks" from a cellulose acetate garment which has been improperly ironed

- 5 A treatment bath is made up (large enough for complete immersion and easy handling of the affected garment) of a 5 gram per litre solution of paratoluenesulphonamide in soft water. The garment is immersed in this at 80° C. and worked
10 for 30 minutes. It is thereafter washed and dried.

EXAMPLE 3

To delustre 10 kilograms of cellulose acetate woven fabric on the jigger

- 15 800 grams of acetanilide are dispersed with 800 grams of Turkey red oil, and substituted for the paratoluenesulphonamide of Example 1 above.
20 The subsequent procedure is then identical with that of Example 1. Instead of delustering the material by a number of passages through a hot, relatively dilute, dispersion of the acetanilide, the material may first be padded at a temperature
25 of about 85° C. with a dispersion containing about 10% of acetanilide. The material is there-

after allowed to stand for a time and is then delustered by passage through an open tank of substantially boiling water. The material is thereafter washed off, rinsed and dried or otherwise treated as may be desired.

5 What we claim and desire to secure by Letters Patent is:—

10 1. Process for the treatment of cellulose acetate textile materials exhibiting glaze marks, which comprises subjecting said materials to the action of a hot aqueous bath comprising paratoluene sulphonamide and terminating the treatment when the glaze marks are substantially removed and before the remaining parts of the fabric are materially delustered.

15 2. Process for the treatment of cellulose acetate textile materials exhibiting glaze marks, which comprises subjecting said materials to the action of a 0.3 to 1% aqueous bath of paratoluene sulphonamide at a temperature of 80 to 85° C. and terminating the treatment when the glaze marks are substantially removed and before the remaining parts of the fabric are materially delustered.
